VALVE FOR ELIMINATING ODOR AND
SMOKE IN EXHAUST GASES

Lester M. Crabb, Flint, Mich., assignor to General Motors Corporation, Detroit, Mich., a corporation of Delaware

Application May 2, 1932, Serial No. 608,649

2 Claims. (Cl. 137—153)

When the throttle valve of the carburetor of an internal combustion engine is suddenly closed, the exhaust gases become smoky and acquire an obnoxious odor. My experiments have shown that, to a large extent, the smoke and obnoxious odor are the result of the presence of incompletely burned fuel in the exhaust gases.

This invention relates to a method of and apparatus for eliminating incompletely burned fuel and the smoke and obnoxious odor which result therefrom from the exhaust gases of an internal combustion engine during periods of rapid deceleration.

I have found that the presence of incompletely burned fuel in the exhaust gases of an internal combustion engine during periods of rapid deceleration is the result of the failure to supply, during such periods, sufficient air to the cylinders of the engine to completely burn the fuel supplied thereto. My experiments have further shown that this condition can be remedied and the smokiness and obnoxious odor of the exhaust gases resulting therefrom can be eliminated, without affecting the ratio of fuel to air in the combustible mixture supplied to the cylinders of the engine at any other time than during periods of rapid deceleration, by admitting to the induction system of the engine on the engine side of the carburetor, during periods of rapid deceleration only, sufficient air to insure complete combustion of all of the fuel supplied to the cylinders of the engine. The fact that, during periods during which deceleration is so rapid that there is sufficient incompletely burned fuel in the exhaust gases to cause smokiness and obnoxious odors, the pressure in the induction system of an internal combustion engine on the engine side of the carburetor is considerably lower than at any other time during the operation of the engine makes it possible to employ very simple mechanism to effect the admission of air during such periods without affecting the operation of the engine at any other time. In its simplest form, the mechanism may consist merely of a passage through which air may enter the intake manifold of the engine from the atmosphere and a valve urged by the pressure of the atmosphere, from a position in which the passage is closed to a position in which it is open, against the intake manifold pressure and the resistance of a spring which is of such strength that the pressure of the atmosphere will be sufficient to open the passage only when the intake manifold pressure reaches a value below that which it assumes at any time other than when

deceleration is so rapid that sufficient incompletely burned fuel would occur in the exhaust gases to cause them to be smoky and have an obnoxious odor. However, since, when the passage is open, the pressure in the intake manifold immediately rises, it is preferable, in order to maintain the passage open sufficiently long to admit to the intake manifold sufficient air to insure complete combustion of all of the fuel which enters the cylinders of the engine during the period under consideration, to construct and/or arrange the valve so that a smaller difference in pressure is necessary to maintain it in the position in which the passage is open than to move it to this position from the position in which the passage is closed.

For a better understanding of the nature and objects of the present invention, reference is made to the following description of the preferred forms of air admission mechanism which are illustrated in the accompanying drawings.

In the drawings:

Figure 1 shows an internal combustion engine on whose intake manifold there is installed air admission mechanism in accordance with my invention.

Figure 2 is an enlarged fragmentary transverse section through the installation shown in Figure 1, taken on the line 2—2 of Figure 3.

Figure 3 is a section taken on the line 3—3 of Figure 2, showing the valve in closed position.

Figure 4 is a section taken on the line 4—4 of Figure 2, showing the valve in open position.

Figure 5 is a perspective view of a second form of air admission mechanism.

Figure 6 is a perspective view of a third form of air admission mechanism.

Figure 7 is a section similar to Figure 3, but showing a fourth form of air admission mechanism.

Figure 8 is a section taken on the line 8—8 of Figure 7.

Figure 9 is a section similar to Figures 2 and 8, but showing a fifth form of air admission mechanism.

In the drawings, I have illustrated the mechanism for admitting air to the induction system of an internal combustion engine on the engine side of the carburetor during periods of rapid deceleration as applied to the propelling engine of an automotive vehicle because it is particularly useful in connection with such an engine since more people are subjected to the effects of its exhaust gases than to the exhaust gases of stationary engines. On the engine, there is

installed a "duplex" carburetor 18 of which each mixture passage is connected through one of the passages 11 and 12 of an intake manifold 13 to intake ports of the engine.

5 The air admission mechanism which is illustrated in Figures 1 to 4 of the drawings includes a body 14 in which there is provided a cylindrical bore 15 which extends from one end of the body to a point adjacent the other end. The open end 10 of the bore is closed by a head 16 which carries a pin 17 which projects axially into the bore. Into the closed end of the bore 15, there extends a passage in the form of a bore 18 which is of smaller diameter than and disposed coaxially 15 with respect to the bore 15. Over the outer end of the passage 18, there is disposed a dirt 20 excluding shield 19. Within the bore 15, there is snugly fitted to slide a piston valve 20 on whose head end there is provided a coaxial extension 21 of reduced diameter which is adapted to fit snugly within the passage 18. A coil spring 23, of which one end surrounds the pin 17 and of which the other end extends into the interior of the piston valve 20, urges the piston valve to the position 25 in which it is shown in Figure 3 of the drawings. Through the bottom of the body 14 into the bore 15 at such points that they are covered by the piston valve 20 when it is in the position in which it is shown in Figure 3, there extend 30 a pair of bores 24. In the bottom of the bore 15, there is formed a groove 25 which extends from the head end thereof to the plane which includes the axes of the bores 24 and communicates with both of the bores 24 and with the space between 35 the piston valve 20 and the head.

To facilitate installation of the air admission mechanism hereinbefore described, there is preferably provided on the upper surface of the manifold 13 directly above the riser, a plane surface 40 through which into each of the passages 11 and 12 there extends a bore 26. To install the air admission mechanism hereinbefore described on the manifold 13, the former is seated on the plane surface with one of the bores 24 in axial alignment 45 with each of the bores 26 and then secured in place by screws 27 which extend through ears on the body 14 and into the manifold.

The air admission mechanism 28 which is illustrated in Figure 5 is adapted to be installed in 50 the same manner as that illustrated in Figures 1 to 4 and differs from that illustrated in Figures 1 to 4 only in that communication between the bores 24 and the space between the head and the piston valve is established by a bore 29 which 55 extends thereto through the bottom of the body and a groove 30 on the bottom of the body which intersects the bores 24 and 29. It will, of course, be understood that the plane surface on the manifold will form the lower wall of the 60 groove 30 when the air admission mechanism is installed on the manifold in the manner described above.

The air admission mechanism 31 which is illustrated in Figure 6 is adapted to be installed in 65 the same manner as the mechanisms illustrated in Figures 1 to 5, and differs from the mechanism illustrated in Figure 5 only in that the ears adjacent the head end are eliminated and in that the groove 30 in Figure 5 is replaced by a slot 32 70 which extends completely through the bottom of the body.

The air admission mechanism 33 which is illustrated in Figures 7 and 8 does not differ essentially from that which is illustrated in the 75 preceding figures except in that the two bores 24

are replaced by a single threaded bore 34 and in that communication between the bore 34 and the space between the head and the piston valve 20 is established by intersecting bores 35 and 36. To facilitate installation of the mechanism illustrated in Figures 7 and 8, there is provided in the manifold 37 directly above the riser, a threaded bore 38 which enters both of the passages 11 and 12. The mechanism 33 is preferably connected to the manifold by a hollow externally threaded fitting 39 which is screwed into the threaded bores 34 and 38.

The air admission mechanism which is illustrated in Figure 9 of the drawings, includes a cylindrical body 41 in which there is provided a 15 cylindrical bore 42 which extends from one end thereof to a point adjacent the other end and on which there is provided a reduced coaxial threaded extension 43 through which there extends coaxially into the bore 42 a bore 44 which is 20 of smaller diameter than the bore 42.

Into the end of the body 41 opposite that on which the extension 43 is provided, there is threaded an annular valve seat 45. Within the bore 42, there is located a valve 46 which has a 25 longitudinally grooved cylindrical body which is adapted to slide in the bore 42 and a tapered outer end which is adapted to seat on the walls of the opening in the seat 45. A coil spring 47 which is located within the bore 42 urges the 30 valve 46 to the position in which it is shown in the drawings in which it functions as a closure for the opening in the seat 45.

The air admission mechanism which is illustrated in Figure 9 is adapted to be installed on 35 the manifold 49 by screwing the extension 43 into a threaded opening 48 which communicates with both of the branches 11 and 12 of the manifold.

It will be noted that the valves 20 and 46 of the air admission mechanisms illustrated in the 40 drawings and hereinbefore described are so disposed that they may be moved from positions in which they permit the passage of air from the atmosphere into the passages 11 and 12 of the intake manifolds (through the passage 18 and the 45 bores 15, 24, and 26 in Figures 1 to 5; through the opening 18, the bore 15, the slot 32 and the bores 26 in Figure 6; through the opening 18 and the bores 15, 34 and 38 in Figures 7 and 8; and through the opening in the seat 45, the 50 grooves in the valve 46 and the bores 42, 44, and 48 in Figure 9) to positions in which they prevent the passage of air from the atmosphere into the passages 11 and 12. It will be further observed that the springs 23 and 47 urge the valves 20 and 46 to the latter positions and that since the pressure of the atmosphere is applied to the outer ends of the valves and the pressure within the passages 11 and 12 to the inner ends of the valves (through bores 26 and 24 and the groove 55 25 in Figures 1 to 4; through bores 26, the groove 30 and the bore 29 in Figure 5; through the bores 26 and the slot 32 in Figure 6; through the bores 38, 34, 35, and 36 in Figures 7 and 8; and through the bores 48, 44, and 42 in Figure 9), reduction of pressure within the passages 11 and 12 60 tends to move the valves to the former positions. As hereinbefore mentioned, the pressure within the passages 11 and 12 during periods during which deceleration is so rapid that sufficient incompletely burned fuel would occur in the exhaust gases to cause them to be smoky and have an obnoxious odor is considerably less than at any other time during the operation of the engine, and, consequently, to insure that admission 65 70 75 76

of air will take place during these periods and at no other time, it is only necessary to make the springs 23 and 47 of such strength that the difference between the pressure of the atmosphere on the portions of the valves on which it is exerted when the valves are in positions in which the passages which connect passages 11 and 12 to the atmosphere are closed, and the pressure within the passages 11 and 12 will move the valves to such positions that they will permit the entrance of air into the passages only when the difference between the pressure of the atmosphere and the pressure within the passages exceeds that which obtains under any other conditions of operation of the engine. It will, of course, be obvious that the admission of air will begin only when the difference between the pressure of the atmosphere and the pressure within the passages 11 and 12 exceeds this predetermined value, but that since, when the valves reach positions in which the passages which connect the passages 11 and 12 with the atmosphere are open, the areas of their end surfaces on which the pressure of the atmosphere is exerted are greater than those on which the pressure of the atmosphere is exerted when the passages are closed, the valves will remain in the positions in which the passages are open until the difference between the pressure of the atmosphere and the pressure within the passages 11 and 12 falls below a predetermined value which is less than that necessary to move them to positions in which the passages are open. Since the length of time during which the valves remain in positions in which the passages are open is determined by the difference between the areas of the end surfaces of the valves on which the pressure of the atmosphere is exerted when the passages are open and when the passages are closed, the volume of air admitted to the passages 11 and 12 between the time the valves reach positions in which the passages are open and the time the valves return to positions in which the passages are closed is determined by the difference between the areas of the end surfaces of the valves on which the pressure of the atmosphere is exerted when the passages are open and when the passages are closed. Consequently, while if the areas of the end surfaces of the valves on which the pressure of the atmosphere is exerted when the passages are open are made sufficiently larger than the areas of the end surfaces on which the pressure of the atmosphere is exerted when the passages are closed, the passages will remain open sufficiently long to admit to the passages 11 and 12 sufficient air to insure complete combustion of all fuel which enters the engine cylinders and to eliminate smoke and odors in the exhaust during periods of rapid deceleration, air will not be admitted to the passages 11

and 12 through the passages which connect them with the atmosphere at other times than during periods of rapid deceleration if the springs 23 and 47 are made of such strength that the difference between the pressure of the atmosphere on the portions of the valves on which it is exerted when the valves are in positions in which the passages which connect the passages 11 and 12 to the atmosphere are closed and the pressure within the passages 11 and 12 will become sufficient to move the valves to positions in which the passages are open only during periods of rapid deceleration.

I claim:

1. In mechanism for regulating admission of air into the passage connecting the carburetor to cylinders of an internal combustion engine, a valve housing in which there is provided a bore which is closed to the atmosphere at one end, a smaller bore extending into the other end of the first mentioned bore and communicating with the atmosphere, a valve which fits and is slideable in the first mentioned bore and on which there is provided an extension which fits and is slideable in the second mentioned bore, a spring urging the valve to a position in which the extension is located in the second mentioned bore, a passage adapted to be connected with the first mentioned passage and extending into the first mentioned bore at such a point that it is closed to the atmosphere by the valve when the valve is in the position to which it is urged by the spring, and a passage which communicates with the second mentioned passage and the end of the first mentioned bore which is closed to the atmosphere.

2. In mechanism for regulating admission of air into the passage connecting the carburetor to cylinders of an internal combustion engine, a valve housing in which there is provided a bore which is closed to the atmosphere at one end, a smaller bore extending into the other end of the first mentioned bore and communicating with the atmosphere, a valve which fits and is slideable in the first mentioned bore and on which there is provided an extension which fits and is slideable in the second mentioned bore, a spring urging the valve to a position in which the extension is located in the second mentioned bore, a passage which is adapted to be connected with the first mentioned passage, communicates with the end of the first mentioned bore which is closed to the atmosphere and extends into the first mentioned bore at such a point that it communicates with the atmosphere through the mentioned bores when the extension is withdrawn from the second mentioned bore and is closed to the atmosphere when the valve is in the position to which it is urged by the spring.

LESTER M. CRABB. 60
